US00D753398S

(12) **United States Design Patent**
Arami

(10) **Patent No.:** US D753,398 S
(45) **Date of Patent:** ** Apr. 12, 2016

(54) **PROTECTOR FOR A TZITZIT OR A SIMILAR RELIGIOUS ARTICLE**

D627,167 S * 11/2010 Kittrell D3/299
D632,078 S * 2/2011 Schmitz D3/299
D708,851 S * 7/2014 Cooper D3/20

(71) Applicant: **Roey Arami**, Kfar Shalem (IL)

* cited by examiner

(72) Inventor: **Roey Arami**, Kfar Shalem (IL)

Primary Examiner — Holly Bayham

(**) Term: **14 Years**

(74) *Attorney, Agent, or Firm* — Nath, Goldberg & Meyer;
Jerald L. Meyer

(21) Appl. No.: **29/491,460**

(57) **CLAIM**

The ornamental design for protector for a tzitzit or a similar religious article, as shown and described.

(22) Filed: **May 21, 2014**

DESCRIPTION

(51) **LOC (10) Cl.** 03-01

FIG. 1 is a perspective view of the claimed design;

(52) **U.S. Cl.**

FIG. 2 is a top view thereof;

USPC **D3/299**

FIG. 3 is a bottom view thereof;

(58) **Field of Classification Search**

FIG. 4 is a top view; the bottom view is identical thereof;

USPC D3/299, 247, 249-253

FIG. 5 is a left side view thereof;

CPC A45C 1/06

FIG. 6 is a right view thereof;

See application file for complete search history.

FIG. 7 is a folded view thereof; and,

(56) **References Cited**

FIG. 8 is a rolled view thereof.

U.S. PATENT DOCUMENTS

The broken lines representing stitching are part of the claimed design.
